UNITED STATES PATENT OFFICE.

CHARLES C. TOMKINSON, OF PLAINFIELD, NEW JERSEY, ASSIGNOR TO J. EDWARD OGDEN, OF MOUNTAINVILLE, NEW YORK.

CONCRETE INSERT.

Application filed January 27, 1921. Serial No. 440,354.

To all whom it may concern:

Be it known that I, CHARLES C. TOMKINSON, a citizen of the United States, and a resident of Plainfield, county of Union, and State of New Jersey, have invented certain new and useful Improvements in Concrete Inserts, of which the following is a specification.

This invention relates to concrete inserts adapted to form supports for anchoring means such as nuts or headed bolts and it is an object of the invention to form the inserts of sheet metal in such manner that the anchors are effectually supported against withdrawal therefrom under load. Another object of the invention is to form the inserts in such manner that after being imbedded in concrete they shall offer great resistance to withdrawal therefrom.

With the foregoing and other objects in view, the invention consists in the novel construction, combination and arrangement of parts to be hereinafter specifically described in connection with the accompanying drawings forming part of this specification, reference being had, however, to the appended claims for the scope of the invention.

Referring now to the drawings. Fig. 1 is a perspective view of one embodiment of my invention, the insert being arranged for the removable and slideable securement of an anchor in the form of a headed bolt.

Fig. 2 is a view similar to Fig. 1 of another embodiment of my invention showing the insert arranged for the fixed securement of an anchor nut.

Fig. 3 is a cross section taken on the plane of line 3—3 of Fig. 1 showing the ledges for supporting the anchors as being U-shaped in cross section.

Fig. 4 is a view similar to Fig. 3 but showing the said ledges as of rolled form instead of U-shaped.

Fig. 5 is another view similar to Fig. 3 but showing the said ledges in the form of angular flanges.

Fig. 6 is an end elevation of two of the inserts in "nested" position for shipment.

Fig. 7 is a bottom plan view of a modified form of my invention wherein the anchor supporting ledges are shown as corrugated or crimped throughout their length.

Fig. 8 is a cross section taken on the plane of line 8—8 of Fig. 7.

Like characters of reference designate 55 corresponding parts in all of the figures of the drawings.

Referring to Figs. 1 and 2 it will be seen that the insert consists of an open-sided box indicated generally by 10. This box is surrounded by a gable roof indicated generally by 11. Rising from the ridge of the roof is a web 12 having oppositely extending wings 13. In Fig. 1 the insert is shown as made up of two separate symmetrical sheet metal 60 plates while in Fig. 2 the insert is shown as made or pressed from a piece of tubing.

When the insert is made from tubing the wings 13 are preferably made by slitting the web and then bending the adjacent sections 65 in opposite directions as shown; when made from two symmetrically formed plates the wings are preferably formed by bending over in opposite directions a section of each plate. However, it will be apparent that the 70 wings may be formed in the same manner as those in Fig. 2. The two plates may be secured in fixed relation as by spot welding but preferably by an arrangement consisting of tongues 14 stamped out of one of the 75 plates and entered into slots 15 in the other plate and bent over as shown in Fig. 1. If desired a piece may be cut out of the wings and web at C to reduce the weight of the 80 insert.

The box 10 is shorter in length than the 85 length of the ridge of the roof 11; the gables 11 therefore overhang the ends 16 of the box. This arrangement is an important feature of the invention since not only is the 90 material of the plates or tube used to the best possible advantage and without waste but by reason of the overhanging gables thus formed, the insert is more firmly held 95 against withdrawal from the concrete structure.

Another important feature of the invention is the manner in which the bottom edges of the box are utilized to form ledges or rails for supporting the anchoring means 100 (bolt head or nut). In carrying out this feature of the invention, the corners of the box 10 are slit or cut away for a short distance. The edges of two opposite sides of the box are then bent inwardly to form the ledges 105 indicated generally by 17. These ledges are preferably bent over so as to form one leg "a" of a U, the adjacent wall forming the

other leg as clearly indicated in Figs. 1 and 3. While this U-form is preferred, the invention is not limited to that construction for as shown in Figs. 4 and 5 at "b" and "c," respectively, the ledges may be rolled over until closed by contact with the adjacent walls or may extend from the side walls at right angles.

In order to give additional stiffness to the ledges 17, I may crimp or corrugate them as shown by "d" in Figs. 7 and 8 regardless of whether they are in one or other of the forms shown in Figs. 3, 4 or 5. In order to further strengthen the ledges, I may provide suitable fillers "e" to be inserted between the adjacent side walls and bent over ledges as shown in Figs. 4 and 8.

After the ledges 17 have been formed or bent over the sections at the ends of the box 10 are bent over at right angles to form the lateral extensions or tabs 18. These tabs are notched as at 19 to provide for the passage of nails or other means for securing the insert to a fixed support as a mold while the concrete is being poured.

In Fig. 2 I have shown the box 10 as housing an anchoring means in the form of a nut N in relatively fixed position. The edges of the roof 11 form abutments on one side of the nut and the ledges 17 on the other side prevent it from dropping out. When the insert is made from a piece of tubing as in Fig. 2 the nut will of course be inserted before the ledges 17 are formed.

On the other hand when the insert is composed of two pressed plates as in Fig. 1, the nut may be inserted after the ledges 17 are pressed but prior to the securing of the plates at their webs.

As shown in Fig. 1, the insert may be of sufficient length to allow for the slidable adjustment of the anchors. In order to provide for the entry or removal of a bolt or headed anchor, the ledges 17 are not extended the full length of the box but terminate short of one end thereof to provide a gateway G. The distance between this end and the adjacent terminals of the ledges is preferably less than the width of the box (assuming that the head of the bolt or anchor is square) in order to make necessary the placing of the bolt in an inclined position to permit its insertion or removal or in other words to prevent the anchor from being pulled out through the gateway when the anchor bolt is in normal position. The material left unbent as a ledge at the gateway is turned back as flaps 20 against the side walls of the box.

While I have described the invention in great detail, it is to be distinctly understood that the showing is merely illustrative and is therefore not to be taken in a limiting

sense—I intend no limitations other than those imposed by the appended claims.

65

What I claim is:

1. A sheet metal concrete insert comprising a pair of stampings secured together and forming a box adapted to house an anchor and having walls for supporting an anchor, a roof surmounting the box, webs extending from the ridge of the roof and flanges on the webs.

2. A sheet metal concrete insert comprising a pair of symmetrical stampings secured together and forming a box adapted to house an anchor and having walls for supporting an anchor, a roof surmounting the box, webs extending from the ridge of the roof and flanges on the webs.

75

3. A concrete insert comprising a box, a roof surmounting the box and a substantially flat web extending from the ridge of the roof, the heights of the box, roof and web being equal.

80

4. A concrete insert comprising a box, a roof surmounting the box and a substantially flat web extending from the ridge of the roof, the heights of the box, roof and web being equal, the plane of the web bisecting the roof and box.

85

5. A sheet metal concrete insert comprising a pair of symmetrical stampings, each stamping having a side wall and end walls, a roof portion bent inwardly from the side wall and having end walls bent outwardly from the first mentioned end walls, a web extending in alinement with the inner edges of the end walls and a laterally extending flange on the web.

90

6. A sheet metal concrete insert comprising a pair of symmetrical stampings, each stamping having a side wall and end walls, a roof portion bent inwardly from the side wall and having end walls bent outwardly from the first mentioned end walls, a web extending in alinement with the inner edges of the end walls and a laterally extending flange on the web, each side wall having a portion of its lower edge bent inwardly to form a ledge.

100

7. A sheet metal concrete insert comprising a pair of symmetrical stampings, each stamping having a side wall and end walls, a roof portion bent inwardly from the side wall and having end walls bent outwardly from the first mentioned end walls, a web extending in alinement with the inner edges of the end walls and a laterally extending flange on the web, the webs of the two stampings having interengaging portions for securing the stampings together.

115

In witness whereof, I have hereunto set my hand this 17th day of January, 1921.

CHARLES C. TOMKINSON.
